UNITED STATES PATENT OFFICE

ERNEST WALTER ROSE, OF RESERVOIR, AUSTRALIA

FORMATION OF CONCRETE BUILDINGS

Application filed July 20, 1926, Serial No. 123,750, and in Australia August 18, 1925.

This invention relates to improvements in or relating to the formation of concrete buildings and refers especially to the construction of hollow concrete walls—that is to say, walls 5 in which cavities are formed—by the aid of moulds or forms which, when placed in position will permit the concrete to be poured continuously or in one operation from floor to ceiling.

10 The object of the present invention is to provide improvements in the construction of moulds or forms and means for easily and conveniently erecting and dismantling the same whereby hollow walls may be erected 15 for the construction of a building with greater facility than heretofore and to make provision for ensuring a satisfactory ventilation of the spaces within the hollow walls and below the floors of a building.

20 I accomplish the abovementioned objects by providing foundations, having means on the top thereof to correctly align the forms or moulds for constructing the inner and outer sections of the walls and in providing vents 25 in the said foundations adapted to communicate with the space between the inner and outer sections of the wall.

The invention also embodies means for 30 erecting hollow walls of concrete buildings, comprising in combination with exterior forms, vertical or approximately vertical rows of ties adapted to connect the inner and outer sections of the walls together, two or more opposed pairs of interior forms arranged between adjacent vertical rows of 35 ties, removable locking bars inserted between and adapted to retain the interior forms the required distance apart to determine the width of the wall cavity, and means for effecting 40 a close junction between adjacent forms to prevent seepage.

In order that the invention, the object and nature of which have been set forth, may 45 be readily understood, reference will now be had to the accompanying sheets of explanatory drawings wherein:—

Figure 1 is a view in section end elevation 50 of a lintel and part of a hollow concrete wall with moulds or forms in position and constructed in accordance with the invention.

Figure 2 is a view in side elevation of a lintel and portion of the wall and moulds or forms shown in Figure 1.

Figure 3 is a view in plan of Figure 1.

Figure 4 is a view in sectional end elevation 55 of a modified form of lintel or beam.

Figure 5 is a view in perspective of portion 60 of the interior moulds or forms and is drawn to a larger scale than the preceding figures.

Figure 6 is a view in sectional side elevation taken on the line 6—6 of Figure 1.

Figures 7 and 8 are detail views of tubular 65 wall ties used in connection with the invention.

Figure 9 is a view in perspective similar to Figure 5 of another portion of the interior form.

Figure 10 is a view in plan of portion of a 70 lintel or beam.

Figure 11 is a view in plan showing those 75 portions of the moulds or forms for constructing a corner of a building.

Figures 12 and 13 are views in sectional end elevation showing modifications of portions 80 of interior moulds or forms and hereinafter will be fully described.

Figure 14 is a view in plan of portion of a wall and moulds or forms constructed of metal and made in accordance with the invention.

Figure 15 is a view in plan of portion of the interior form shown in Figure 14 and drawn to a larger scale.

Figure 16 is a view in plan illustrating a 85 modification in construction of the corner portion of an internal mould or form, and hereinafter will be fully described.

Figure 17 is a view in plan showing diagrammatically a further modification of the 90 invention and hereinafter is fully described.

In proceeding to the construction of a building in accordance with the invention, the foundations are laid in the usual way either continuously or interruptedly; in the latter 95 case (which is illustrated in Figures 1 and 2 of the drawings) suitable pillars or columns 20 are provided to carry lintels 22 upon which the walls 21 are formed.

When the foundation has set, the lintels or 100

beams 22 are placed end to end around the whole length thereof and the same are correctly aligned both vertically and horizontally by placing cement grouting or packing beneath the same. The lintels or beams 22 are preferably connected together by means of tie bars (not shown) or if desired they may be moulded in position on the job in such a manner as to effect a continuous structure.

10 The lintels or beams 22 are slightly wider than the wall 21 and their upper surfaces are formed with longitudinally disposed raised portions 23 which align with and are of the same width as the two sections of the wall 21 to be built. These longitudinally disposed raised portions serve as locating abutments for the lower ends of outer forms 24 and internal forms 25 which extend the whole length of the lintels or beams.

15 20 Suitable damp courses 26 are placed on the longitudinally disposed raised portions 23, or alternatively, in the case of continuous foundations the damp course may be placed below the lintels or beams 22. If desired the damp courses 26 may be moulded upon and form a part of the said lintels or beams 22.

25 30 If desired the longitudinally disposed raised portions 23 may be formed on the top of the foundation and in this construction the separately formed lintels or beams 22 are dispensed with.

35 The lintels 22 or foundations are formed with a longitudinally extending channel or sump 27 which is disposed in line with the wall cavity and is adapted to accommodate any thin or watery concrete that may pass between the internal forms 25, thus avoiding accumulation of the same around the lower ends of the internal forms in such a manner as to 40 interfere with or prevent their subsequent withdrawal.

45 Furthermore, as the sump or channel 27 is disposed well below the damp courses 26 the accumulation of thin concrete cannot collect above the course and form a leakage path for moisture by bridging the two portions of the wall 21 above the damp courses.

50 A series of vertical vents or outlets 28 which communicate with the sump 27 are formed in the lintels or beams 22 and the same serve to discharge any leakage of concrete which might accumulate in the said sump or channel 27.

55 It will be understood that the sumps do not necessarily take the form of continuous channels as shown in the drawings, as they may with equal facility comprise a series of separate troughs formed in the lintels or foundations, each of which may be provided with 60 vents or discharge outlets.

65 Grating or netting (not shown) is preferably placed over the vents 28 in order to prevent the entrance of vermin and if desired the said grating or netting may be inserted in 70 the lintels during the course of manufacture.

When continuous foundations are adopted horizontal vents 29 are provided in the lintels or beams 22 in lieu of the vertical vents 28 and the same are preferably provided with covers 30 (see Figures 1 and 2.)

70 The lintels 22 are also provided on one side with continuous ledges 22' which are adapted to support the ends of the floor joists 31 when timber floors are used.

75 In a modified construction (see Figure 4) the lintels or beams may be composed of two members 22'' and 22''' which are connected one to the other by means of ties 32 the space between the said members serving as a vent and a passage for watery concrete.

80 The opposed sections of the wall 21 are held together by means of ties 33 which are arranged in vertical or approximately vertical rows as shown clearly in Figures 1, 2 and 6 of the drawings.

85 The outer forms 24 are held in position by means of bolts 35 and in order that the latter may be withdrawn without difficulty after the concrete forming the walls has set, the ties 33 are preferably of tubular construction 90 and are adapted to accommodate the said bolts. In order that the ties may have a firm grip in the inner and outer sections of the walls they may be fitted or formed with projections or collars 34.

95 100 The bolts 35 are adapted to retain brackets 36 in position on the said outer forms and the said brackets are provided with bracing bars 37 of wood or other material which bear against and prevent bulging or other movement of the outer forms 24.

105 110 The tubular ties 33 may, if desired, be formed with flared ends 33' (see Figures 1, 7 and 8) in order to obtain a firmer grip in the walls and when the ends are flared or bell-mouthed, the projections 34 may be dispensed with (see Figure 8).

115 120 The tubular ties 33 are preferably placed in such positions that when the walls are moulded and the forms removed wood plugs 38 (Figure 7) may be driven into the ends thereof so that skirting boards, picture railings and architraves or the like may be conveniently secured thereto.

125 130 Any tubular ties 33 which are not required for the last mentioned purpose may be plugged with cement and finished off in the usual way after the bolts 35 are withdrawn.

135 140 If desired tie bar 39 shown in chain-dotted lines in Figure 1 may be used in lieu of tubular ties 33 where the latter are not required.

145 150 Two or more sets of internal core forms 25 are preferably inserted between each adjacent pair of vertical rows of ties 33 and the edges of the forms situated farthest from the said rows of ties 33 are separated by means of flaps or extensions 40 which are attached to one of each pair of internal forms 25 by hinges 41 (see Figures 3, 6 and 9).

The edges of the internal core forms lying along the rows of ties 33 are provided with notches or gaps 33'' which are adapted to accommodate the said ties.

5 The internal forms 25 are preferably constructed of a series of suitably braced horizontally or vertically disposed boards extending the full height of the wall 21 and held together by means of battens 42. Vertical members 43 (preferably V-shaped) are secured to the edges of the forms adjacent to the vertical rows of ties 33 and the same are also provided with gaps or notches 33'' which are adapted to accommodate the said ties (see 10 Figure 5).

15 Each pair of opposed V-shaped members 43 is adapted to be engaged by a corresponding-ly shaped removable bar 44 which may be pro-20 vided with end pieces 45 adapted to retain the forms 25 in position until the concrete is 25 poured.

25 Removable locking bars 46 are adapted to be placed between the battens 42 and V-shaped members 43, and the same are fitted with anti-friction rollers 47 which bear outwardly on the internal forms 25. If desired, anti-friction rollers 48 can be fitted to the locking bars 46 so as to bear against the removable bars 44 in order to facilitate the removal of the 30 said locking bars when the walls have set.

The locking bars 46 may be parallel but, if desired, they may be tapered slightly in order that they may be removed with greater freedom.

35 The edges of the internal forms remote from the ties 33 are maintained the requisite distance apart by means of locking bars 49 fitted with anti-friction rollers 50 which preferably engage metal plates 51 slidably inserted against the hinged flaps 40 (Figure 9).

40 The locking bars 46 and 49 are fitted with bars 52 having holes 53 therein adapted to receive lifting tackle but it will be understood that the locking bars may be fitted with any 45 other suitable device adapted to facilitate the removal of the same.

50 The contiguous sections of the internal forms are preferably held together by means of bolts 62 and 63 which are inserted when the locking bars have been placed in position.

55 Although the drawings indicate constructions wherein each set of forms extends the full height of the walls, they may, if desired, be made in two or more series of forms placed one on top of the other in order to effect the same result.

60 In constructing the corner of a building a key 54 may be utilized, the same being pro-65 vided with anti-friction rollers 55 adapted to transmit pressure to the outer members of the internal forms 25 and to bearing members 56 which bear against the battens 42 positioned adjacent thereto. Locking bars 46 may also be provided and these bars are positioned as 65 close as possible to the corner.

Angle shaped members 58 and 59 may be fitted to the forms 25 to prevent seepage.

When the inner and outer forms have been erected to the full height of the ceiling, as shown in the drawings, the concrete is poured and when the same has set the outer forms are removed by first withdrawing the bolts 35 and removing the brackets 36 and bracing bars 37. 70

The locking bars 46 and 49 and corner keys 54 of the inner forms are then removed after the bolts 62 and 63 have been withdrawn, lifting tackle being used for this purpose if necessary and when the same are removed the bars 44, metal plates 51 and bearing members 56 may be taken out without difficulty, 75 80 whereby the opposed sections of the forms 25 may be moved away from the faces of the cavity in the wall.

In order that the forms 25 may clear the ties 33, the hinged flaps 40 are folded back as indicated in chain dotted lines at 40' in Figures 3 and 9 so that the forms may be moved longitudinally as shown in Figure 6 away from the ties so that the forms can then be removed by lifting them vertically from the 90 cavity in the formed wall.

It will be understood that the bars 44 and plates 51 are not essential parts of the construction as they serve mainly to prevent seepage of thin concrete through the joints 95 between the form sections, and as before-mentioned any concrete that does pass into the cavity is collected in or drains from the sump or channel 27 below the damp courses 26.

In a modified form of the invention (see 100 Figure 12) the locking bar 46 may be made in two oppositely tapered sections 46' and 46'' having anti-friction rollers 47 inserted therebetween and fitted to one or other of the said sections.

Similarly Figure 13 is a sectional end elevation of a modified form of locking bar 49 which is made in two oppositely tapered sections 49' and 49'' having anti-friction rollers 50 inserted therebetween. 110

If desired, the corner keys 54 may also be made in two oppositely tapered sections as indicated by chain dotted lines in Figure 11.

The outer forms 24 and the inner forms 25 may be lined with sheet metal (see dotted lines at 25', Figure 5) in order that the same may be removed from the wall with greater freedom when the walls have set. 115

In order to prevent the locking bars or other members associated with the internal forms from falling into the sump or trough, projections 60 may be formed on the lintels or beams 22 (Figure 10) to support the lower ends of the same, or alternatively the width of the sump may be reduced to effect the same 120 purpose. 125

When it is desired to construct the forms of metal plates they may be arranged as indicated in Figures 14 and 15 wherein the locking bars 46 and 49, the corner keys 54 and 130

the hinged flaps 40 are made of wood as in the construction previously described.

5 The bearing members 56 are preferably fitted with steel plates 56' which take the thrust of the rollers 55 and the angle iron stiffeners or battens 61 and the ends of the metal forms at the corners may be fitted with vertically disposed angle shaped members 58 and 59 to prevent leakage of the concrete.

10 Figure 16 illustrates an alternative design 10 of form for forming a corner of a building and in this construction the sections of the forms 25 are hingedly connected together and are maintained in position at the top 15 and bottom by removable blocks 64. Locking bars 46 indicated on the one side in chain dotted lines are also preferably positioned as near to the corner as practicable.

When the locking bars and blocks 64 are 20 removed the hinged forms may be opened away from the walls as shown so that they can be easily removed from the cavity.

Figure 17 indicates in plan a modified 25 form of the invention wherein three opposed pairs of inner forms 25 are disposed between adjacent vertical or approximately vertical rows of ties 33, locking bars 46 which may be solid or formed in oppositely tapered sections being inserted therebetween. In this 30 construction, the flaps or extensions 40 are dispensed with as in dismantling the central opposed pair of forms are removed from the cavity first, thus allowing the necessary 35 endwise movement of the forms engaging the ties 33.

It is obvious that two or more storied 40 buildings could be constructed in accordance with the invention without difficulty; for example when the walls between the ground and first floors have been erected and the forms therefor dismantled a further series of 45 lintels or beams (preferably of the type shown in Figure 4) having longitudinally disposed raised portions 23 formed thereon may be fitted to the top of the wall in order 50 to align with the wall sections to be built thereon and locate the forms therefor.

Alternatively the longitudinally disposed 55 raised portions may be formed on top of the wall sections disposed between the ground and the first floors of the building and in this case longitudinally extending battens may be removably fitted to the wall near the top thereof in order to locate the forms for the 60 wall extending between the first floor and the ceiling thereof.

The advantages of forming walls upon 65 lintels or beams mounted on foundations or upon pillars or columns and having longitudinally extending troughs or sumps therein as above described are that the said lintels or beams can be readily set in horizontal and vertical alignment and the forms erected correctly thereon to permit of the walls being 70 constructed quite plumb without necessitat-

ing an undue adjustment or manipulation of the parts; the sump prevents the accumulation of thin concrete above the damp courses, and furthermore, the vents ensure a good ventilation throughout the wall 70 cavity.

A further advantage accruing from the construction of buildings in accordance with the present invention is due to the saving of material in the damp courses which comprise 75 (in the present invention) two relatively narrow strips extending around the building instead of a single strip the full width of the wall as in the usual building construction. As a result of the smaller amount of material required, sheet zinc or the like, which is often prohibitive on the grounds of expense, may be utilized for the damp courses.

I claim:

1. In devices for erecting concrete buildings having hollow walls, the inner and outer sections of which are adapted to be connected by vertical or approximately vertical rows of ties, two or more opposed pairs of interior forms arranged between adjacent rows of ties, notches in contiguous edges of the forms to accommodate the wall ties, removable spacing members between edges of the forms remote from the wall ties and adapted when moved to permit of longitudinal movement of the forms in the wall cavity, and removable locking bars adapted to retain the interior forms a required distance apart. 90

2. In devices for erecting hollow walls of concrete buildings, the combination, with exterior forms, of vertical or approximately vertical rows of ties adapted to connect the opposed sections of the walls together, two or more opposed pairs of interior forms arranged between adjacent rows of ties, removable locking bars inserted between and adapted to retain the interior forms the required distance apart to determine the width of the wall cavity, notches adapted to accommodate the ties, formed in one end of each of the interior forms and hinged flaps or extensions attached to the internal forms and adapted to space the same longitudinally whereby when the hinged flaps are swung inwardly 115 away from the wall the forms are capable of endwise movement to clear the ties. 110

3. In means for erecting hollow walls of concrete buildings, interior and outer forms adapted to be supported by ledges formed on a foundation, vertical rows of ties adapted to connect opposed sections of the walls together, two or more opposed pairs of internal forms arranged between adjacent rows of ties, notches in the edges of the forms adapted to 125 accommodate the ties, flaps or extenions hinged to the forms intermediate the rows of ties and adapted, when folded inwardly away from wall, to allow of longitudinal movement of the forms to clear the ties, and locking 130

bars inserted between each opposed pair of internal forms.

4. In devices for erecting hollow walls of concrete buildings having vertical or approximately vertical rows of ties connecting the inner and outer sections of a wall, two or more opposed pairs of interior forms arranged between and having notched edges accommodating adjacent rows of ties, locking members adapted to retain the forms a required distance apart, and hinged flaps or extensions attached to the edges of the forms remote from the ties and adapted to space the said forms longitudinally whereby when the hinged flaps are swung inwardly away from the wall the forms are capable of end movement to clear the ties.

5. In devices for erecting hollow walls of concrete buildings, the combination, with exterior forms, of vertical or approximately vertical rows of ties connecting the inner and outer sections of the wall, two or more opposed pairs of interior forms arranged between the adjacent rows of ties, locking elements inserted between and adapted to retain the opposed pairs of interior forms a required distance apart, and means for retaining the contiguous or adjacent edges of the interior forms close together in juxtaposition when erected.

6. In the construction of concrete buildings as claimed in claim 1, bolts adapted to hold the adjacent inner forms together.

7. In devices for erecting hollow walls of concrete buildings having vertical or approximately vertical rows of ties connecting the inner and outer sections of the wall, two or more opposed pairs of interior forms arranged between adjacent rows of ties, removable locking elements inserted between and adapted to retain the interior forms a required distance apart, and cover members on the inside of the joints between the internal forms to prevent seepage.

45 8. In devices for erecting hollow walls of concrete buildings having vertical or approximately vertical rows of ties connecting the inner and outer sections of the wall, two or more opposed pairs of interior forms arranged between adjacent rows of ties, removable locking elements inserted between and adapted to retain the interior forms a required distance apart, vertical V-shaped members secured near to the vertical edges of the forms adjacent the rows of ties, and correspondingly shaped removable bars adapted to engage the V-shaped members and seal the joints to prevent seepage

9. In devices for erecting hollow walls of concrete buildings having vertical or approximately vertical rows of ties connecting the inner and outer sections of the wall, two or more opposed pairs of interior forms arranged between adjacent rows of ties, removable locking elements inserted between

and adapted to retain the interior forms a required distance apart, and oppositely tapered locking bars adapted to bear against each other and retain the interior forms at a required distance apart.

10. In devices for erecting hollow walls of concrete buildings having vertical or approximately vertical rows of ties connecting the inner and outer sections of the wall, two or more opposed pairs of interior forms arranged between adjacent rows of ties, removable locking elements inserted between and adapted to retain the interior forms a required distance apart, pairs of oppositely tapered locking bars adapted to bear against the inner forms, and anti-friction rollers positioned between each pair of locking bars.

11. In devices for erecting hollow walls of concrete buildings, the combination with exterior and interior forms of tubular wall ties adapted to extend through and connect the inner and outer sections of a wall, bolts passing through the tubular ties, and through the exterior forms, brackets retained in position on the exterior forms by means of the said bolts and bracing bars supported by the brackets.

12. In devices for erecting hollow walls of concrete buildings, the combination with exterior and interior forms extending from the floor level to the ceiling, of means for forming the corner of a wall comprising a rectangular key adapted to be inserted between the interior forms and co-acting with bearing members to retain the angle portions of the interior forms in position.

13. In devices for erecting hollow walls of concrete buildings, the combination with the subject matter of claim 1 of means for forming the corner of a wall comprising a rectangular key formed of two or more oppositely tapered portions having anti-frictional members located therebetween to facilitate their removal from a wall cavity, battens on the interior forms and bearing members interposed between the keys and the battens for retaining the interior forms in position.

14. In devices for erecting hollow walls of concrete buildings, the combination with exterior and interior forms extending from the floor level to the ceiling, of means for forming the corner comprising a rectangular key adapted to be inserted between the interior forms and co-acting with bearing members to retain the angle portions of the interior forms in position, and rollers on the exterior of the key or bearing members adapted to facilitate the insertion and withdrawal of the same.

15. In devices for erecting hollow walls of concrete buildings having a series of opposed pairs of interior forms, hinged connections between the interior forms at an angle of a wall, and locking bars adapted to retain the interior forms at a desired distance apart

constructed and arranged whereby when the locking bars are removed the corner forms may be moved away from the inner faces of the wall cavity to permit of the forms being readily removed therefrom.

5 16. In means for erecting hollow walls of concrete buildings upon foundations having longitudinally disposed raised portions arranged between inside and outside ledges, exterior forms supported on the ledges on the outsides of the raised portions, groups of opposed pairs of interior forms resting upon the ledges on the insides of the parallel raised portions, vertically disposed rows of ties supported by the meeting edges of adjacent groups of interior forms, removable locking elements inserted between and adapted to retain the interior forms a required distance apart, notches in the meeting edges of adjacent groups of interior forms to accommodate the wall ties, removable spacing members between edges of the forms remote from the wall ties, and adapted, when removed, to permit longitudinal movement of the forms in the wall cavity, and removable locking bars adapted to retain the interior forms a required distance apart.

10 17. In means for erecting hollow walls of concrete buildings upon foundations having longitudinally disposed raised portions arranged between inside and outside ledges, a sump or channel located between the raised portions, interior and outer forms adapted to be supported by the ledges, vertical rows 15 of ties adapted to connect opposed sections of the walls together, two or more opposed pairs of internal forms arranged between adjacent rows of ties, notches in the edges of the forms adapted to accommodate the ties, flaps or extensions hinged to the forms intermediate the rows of ties and adapted when folded inwardly away from wall to allow of longitudinal movement of the forms to clear the ties, and locking bars inserted between each opposed pair of internal forms.

20 In witness whereof I hereunto affix my signature.

ERNEST WALTER ROSE.
